* cited by examiner

Primary Examiner—Robert A. Delehanty*Assistant Examiner*—Mark Cavanna(74) *Attorney, Agent, or Firm*—Wells St. John P.S.(57) **CLAIM**

The ornamental design for paired bookends, as shown and described.

DESCRIPTION

FIG. 1 is a perspective view of the paired bookends showing my new design.

FIG. 2 is a right side view thereof;

FIG. 3 is a top view thereof;

FIG. 4 is a bottom view thereof;

FIG. 5 is a front view thereof; and,

FIG. 6 is a back view thereof.

The broken lines showing books form no part of the claimed design.
